C. A. YEHLE,
GRINDING BLOCK,
APPLICATION FILED MAY 12, 1920.

1,405,474.

Patented Feb. 7, 1922.

UNITED STATES PATENT OFFICE.

CHARLES A. YEHLE, OF SYRACUSE, NEW YORK.

GRINDING BLOCK.

1,405,474.

Specification of Letters Patent. Patented Feb. 7, 1922.

Application filed May 12, 1920. Serial No. 380,898.

To all whom it may concern:

Be it known that I, CHARLES A. YEHLE, of Syracuse, in the county of Onondaga, in the State of New York, have invented new and useful Improvements in Grinding Blocks, of which the following, taken in connection with the accompanying drawings, is a full, clear, and exact description.

This invention relates to certain improvements in grinding blocks adapted to be magnetically held upon a magnetic bed or carriage, and provided with means for receiving and supporting a thread-cutting tool or analogous implement for grinding the cutting edges thereof as the carriage is moved back and forth across the face of a rotary grinder.

These tools are used for cutting right and left hand threads, and their cutting edges are, therefore, ground on four sides, viz: the top side, opposite upright sides, and in some instances the point, or extreme cutting edge, depending upon the kind of thread desired, the opposite upright sides being usually under-cut or slightly beveled towards the heel of the tool for clearance purposes, it being understood that the side facing the direction of movement of the tool holder is usually ground to a greater angle than that of the opposite side owing to the inclination of the thread.

The object of my invention is to provide a block of magnetizable material with supporting faces adapted to rest upon the bed in such manner that all four faces of the tool may be ground to the desired angle for cutting either right or left hand threads without removing the tool from the block, or in other words permitting four sides of the tool to be ground to the desired angle for right hand threads with one adjustment, and the same number of sides to be ground by simply reversing the tool in the same block.

Another object is to utilize the same opening in the block for receiving tools of different sizes by providing one of the walls of said opening with stepped seats against which the tools of different sizes may be held by a single set screw.

Other objects and uses relating to specific parts of the grinding block will be brought out in the following description:

In the drawings:

Figure 1 is a side elevation of my improved grinding block with the tool therein

in position for grinding the tool to cut right hand threads, the dotted line at the bottom representing the magnetic bed or carriage upon which the lower face of the block rests when used for grinding the upper face of the cutting edge of the tool, a portion of the grinder being also indicated by dotted lines.

Figure 2 is a front face view of the same block with the tool therein, as shown in Fig. 1.

Figure 3 is a side elevation, partly in section, of the same block reversed end for end in the direction of extension of the tool with the tool therein adapted to be ground for cutting left hand threads.

Figure 4 is a front side view of the block with the tool therein, as shown in Figs. 1 and 2, supported upon one of its lengthwise sides for grinding one of the upright sides of the tool to cut right hand threads.

Figure 5 is an end view of the block with the tool therein as shown in Figure 4.

Figure 6 is another front side view with the tool therein as shown in Fig. 4, except that a different side is engaged with the bed or carriage, and that the block is reversed end for end from the position shown in Fig. 4.

Figure 7 is an end view of the block in the position shown in Fig. 6, in which the grinding angle is greater than that produced when the block is in the position shown in Figures 4 and 5.

Fig. 8 is a front side view of the same block in position for grinding one of the upright sides of the tool to cut left hand threads.

Fig. 9 is an end view of the block with the tool therein as shown in Figure 8.

Figure 10 is a front face view of the block as shown in Fig. 8, except that a different side thereof is supported upon the carriage for grinding the other upright face of the tool for left hand thread cutting.

Figure 11 is an end view of the block with the tool therein as shown in Fig. 10.

In order that the successive grinding operations may be clearly understood, it may be stated that in Figs. 1, 2, 4, 5, 6 and 7, the tool remains in the same position of adjustment in the block for grinding different faces thereof for cutting right hand threads, the grinding of the several faces being effected by supporting different sides of the block upon the carriage, while in Figs. 3, 8, 9, 10 and 11, the tool is supported upon the carriage for grinding the upright faces of the tool to cut left hand threads.

10 and 11, the tool is reversed in the block both endwise and transversely to permit its different sides to be ground for cutting left hand threads without removing the tool 5 from the block, by simply supporting different sides of the block flatwise upon the carriage.

The grinding block —1— is adapted to be supported upon an electrically magnetized bed or carriage —A— shown by dotted lines in the several figures, and is preferably made in one piece of magnetic metal, such as machine steel, the bearing surfaces of which may be hardened to reduce wear and 15 assure greater permanency of their relative angular relation.

As illustrated, relatively small portions of zones at both ends of the block are hexagonal and hardened, while the main body may be 20 main unhardened, and is preferably of less cross-sectional area than the end zones, or heads, so that all portions thereof will lie within the planes of the several faces or edges of the end heads, to allow said faces 25 to be easily milled to the desired angles, and also to assure a uniform bearing of those faces or edges throughout their areas upon the supporting bed or carriage, as will be hereinafter more fully described.

30 The end faces, as —2— and —3— of the heads are flat and disposed in parallel planes, while the main body to which the end heads are integrally united, is also hexagonal in cross-section and is provided with a trans- 35 verse tool opening —4— which extends centrally therethrough from side to side in a plane substantially parallel with and midway between the end faces —2— and —3—, and is preferably rectangular in cross-sec- 40 tion, with two of its opposite side walls disposed in planes at substantially right angles to the end faces —2— and —3—, and its other two side walls substantially parallel with said faces for receiving a tool 45 —B— of similar cross section.

This block is provided with a threaded opening —5— extending inwardly from one of its end faces as —3— to the adjacent side of the tool opening —4— at substantially 50 right angles thereto for receiving a set screw —6— by which the tool —B— is held in operative position in the block during the grinding operation.

The side of the opening —4— opposite the 55 set screw —6— is provided with stepped bearings, or seats —7— for receiving tools of different sizes and against which each is held by the set screw —6— when adjusted in the block for grinding.

60 The face of the grinding element —C— shown by dotted lines in Figs. 1, 3, 5, 7, 9 and 11 rotates in a substantially horizontal plane parallel with the surface of the bed or carriage —A—, either the bed or grinder 65 being adjustable vertically to bring the tool

into contact with the grinding surface when its holding block is supported in different positions on the carriage.

As previously stated, the block is hexagonal in cross-section, two of its lengthwise 70 sides, as —8— and —9—, at opposite ends of the opening —4— being disposed in parallel planes at an angle of approximately 15 degrees to the planes of the end faces —2— and —3—, as shown more clearly in 75 Figures —1— and —3—, and, therefore, at the same angle to the plane of the tool when inserted in the opening —4— which is parallel with the end faces —2— and —3—, the cutting end of the tool being adjusted to 80 project some distance beyond one of said faces, as —9—, for grinding the same to cut right hand threads, and is readjusted to project some distance beyond the other face, as —8— of the block, for grinding its several 85 faces to cut left hand threads, in which case the block would simply be inverted from the position shown in Figure —1— to the position shown in Figure —3—.

When the block is standing on either of 90 its end faces, as for example on the end face —2—, with either of the lengthwise faces —8— or —9— at right angles to the eye, as shown in Figure —2—, it will assume a position at an angle of substantially five degrees from a vertical plane, or in other words, its axis will be at an angle of substantially five degrees to a vertical plane 95 for the purpose hereinafter described.

Two of the other lengthwise sides, as 100 —10— and —11— are disposed in planes at an angle of, in this instance, approximately 60 degrees to each other so as to converge toward one of the previously named lengthwise sides, as —8—, or at an angle of approximately 30 degrees to a lengthwise plane 105 passing through the axis of the tool opening —4—, or tool —B— therein when the latter is adjusted in the opening for grinding to cut right hand threads.

The two remaining lengthwise sides, as 110 —12— and —13— of the hexagonal block are also disposed in planes at an angle of substantially 60 degrees to each other, or 30 degrees to that of the tool —B— and its opening —4—, and are adapted to rest upon the surface of the bed or carriage —A— for grinding opposite sides of the tool at angles of approximately 30 degrees to its longitudinal center to cut left hand threads. 115

From the foregoing description, it will be seen that the sides —10— and —13— are directly opposite each other and disposed in parallel planes, while the sides —11— and —12— will also be opposite each other and 120 disposed in parallel planes, each of said sides constituting a substantially flat face adapted to rest upon the surface of the bed or carriage —A— with the tool therein for 125 grinding opposite faces of the cutting edge 130

of the tool to the desired angle at which the threads are to be cut.

In order that the opposite faces of the tool may be under-cut from the cutting edge 5 toward the heel to provide for the necessary clearance of the tool in the work, the end faces —2— and —3— are disposed at an angle of substantially five degrees to the planes of the lengthwise sides —10— and 10 —13— respectively, as shown in Figures —4— and —10— are also disposed in planes at an angle of substantially 10 degrees to those of the lengthwise faces —11— and —12—, respectively, so as to grind the 15 advancing face of the cutting edge of the tool at a steeper angle or greater bevel than the opposite face to clear the incline of the thread as the latter is being cut.

Operation.

Assuming now that it is desired to grind the tool for cutting right hand threads, in which case the tool is secured by the set screw —6— in the opening —4— with its 25 cutting end projecting beyond the lengthwise bearing face —9—, as shown in Figures 1, 2, 4, 5, 6, and 7, the tool supporting block may then be placed with its end face —2— resting upon the magnetic bed or table 30 —A— and magnetically held in position while the carriage is moved back and forth across the underside of the grinder —C— for grinding the upper face of the tool, as shown in Figures —1— and —2—, the face 35 thus ground being parallel with the end face —2— and also square with the tool which is then parallel both longitudinally and transversely with the surface of the bed plate or carriage —A—. The block with the tool 40 therein may then be adjusted with its lengthwise side —10— resting upon the carriage —A— and moved beneath the grinder —C— to grind the cutting face at an angle substantially 30 degrees to the axis of the tool, 45 and also to give it a clearance of approximately 5 degrees from the cutting edge to the cutting end.

The block with the tool therein may then be turned over upon its other side —11—, or 50 to position shown in Figure —7—, and again moved across the underside of the grinder to grind the opposite face of the tool at the same angle, but with slightly greater clearance, in this instance 10 degrees, to avoid 55 friction between the head of the tool and the right hand thread which is then being cut and which inclines in the same direction.

In case it should be necessary to grind the edge of the tool, the block may be supported 60 with its face —8— resting upon the carriage —A— and moved under the grinder —C— to grind the edge, as —b—, parallel with the face —8—, or with a clearance of approximately 15 degrees between the cutting point 65 and heel of the cutting edge.

Assuming again that it is desired to grind the tool for cutting left hand threads, said tool is withdrawn from the side —9— of the block and reinserted in an inverted position in the opposite side —8— of said block with 70 its cutting end projecting some distance beyond the side —8—, as shown in Figures 3, 8, 9, 10 and 11. In order to grind the upper face of the tool, the block is placed with its end face —3— resting upon the carriage 75 —8— and is then moved across the underside of the grinder —C— to bring the upper face of the tool into contact therewith, as shown in Figure —3—, after which it is placed with its side —11— upon the carriage 80 —A— and again moved across the underside of the grinder to grind one side of the tool to the desired angle, as shown in Figures —10— and —11—.

When this operation is completed, the tool 85 is turned over with its side —12— resting upon the carriage —A— and is again moved across the underside of the grinder to grind the other faces of the tool to the desired angle, both angles being substantially the 90 same as those ground for cutting right hand threads, the clearance angles being also the same as described in grinding the tool for cutting righthand threads. That is, in Figures —10— and —11— the block is supported 95 for grinding one side of the tool at a five degree angle of clearance, while in Figures —8— and —9—, it is shown in position for grinding the tool to a 10 degree clearance.

What I claim is:

1. A one-piece grinding block of hexagonal cross-section having its end faces parallel with each other and disposed in planes at an angle to those of each of the sides, said block having two of its sides at 105 opposite sides of its axis parallel with each other and substantially the same width and provided with registering tool openings extending through the block to permit the cutting tool to be inserted in the opening in 110 either side.

2. A one-piece grinding block of hexagonal cross-section having its end faces parallel with each other and disposed in planes at an angle to those of each of the 115 sides, said block having two of its sides at opposite sides of its axis parallel with each other and substantially the same width and provided with registering tool openings extending through the block to permit the cutting tool to be inserted in the opening in either side, and a set screw engaged in a threaded aperture in one end of the block for tightening and loosening the tool in said opening.

3. A one-piece grinding block of hexagonal cross-section having its end faces parallel with each other and disposed in planes at an angle to those of each of the sides, said block having two of its sides at 120

4
opposite sides of its axis parallel with each other and substantially the same width and provided with registering tool openings extending through the block to permit the cutting tool to be inserted in the opening in either side, relatively short portions of the end of the block being extended beyond the intermediate portions of the block.

- 5 4. A grinding block having both ends hexagonal in cross-section and of the same form and area, the intermediate portion of the block being provided with a transverse tool opening extending therethrough from side to side.
- 10 15 5. A grinding block having a transverse

tool opening therethrough and a threaded opening extending inwardly from one end of the block to the tool opening, the walls of the tool opening opposite the threaded opening being gradually reduced in width to receive tools of different sizes and a set screw engaged in the threaded opening for tightening and releasing the tool.

20 In witness whereof I have hereunto set my hand this 3d day of May, 1920.

CHARLES A. YEHLE.

Witnesses:
